US0D1060102S

(12) United States Design Patent (10) Patent No.: US D1,060,102 S
(45) Date of Patent:  Feb. 4, 2025

(54) ITEM OF JEWELLERY

(71) Applicant: ROBERTO DEMEGLIO S.p.A., Turin
(IT)

(72) Inventor: Luca Stefanini, Valenza (IT)

() Term: 15 Years

(21) Appl. No.: 35/519,565

(22) Filed: Nov. 13, 2023

(80) Hague Agreement Data

Int. Filing Date: Nov. 13, 2023

Int. Reg. No.: DM/234030

Int. Reg. Date: Nov. 13, 2023

Int. Reg. Pub. Date: Dec. 29, 2023

(51) LOC (15) Cl. 11-01

(52) U.S. Cl.

USPC D11/4
